REEL FOR DISPENSING TAPES AND OTHER LIKE GOODS

Filed Jan. 5. 1923

Patented Mar. 17, 1925.

1,530,062

UNITED STATES PATENT OFFICE.

JOHN W. THOMPSON, OF OAK PARK, ILLINOIS, ASSIGNOR TO MARSHALL FIELD & COMPANY, OF CHICAGO, ILLINOIS, A CORPORATION OF ILLINOIS.

REEL FOR DISPENSING TAPES AND OTHER LIKE GOODS.

Application filed January 5, 1923. Serial No. 610,738.

To all whom it may concern:

Be it known that I, JOHN W. THOMPSON, a citizen of the United States, residing at Oak Park, in the county of Cook and State 5 of Illinois, have invented certain new and useful Improvements in Reels for Dispensing Tapes and Other like Goods, of which the following is a specification.

This invention relates to a reel of a construction which adapts it to be mounted along with other similarly constructed reels upon a single support or shaft, and to pay out a tape, ribbon, or other commodity wound thereon without interference with 10 an adjacent reel or reels and without any tendency to cause an adjacent reel to revolve and unwind its contained goods.

The object of the invention is to provide a reel construction which will not only be 20 cheap enough to be discarded when empty, but will be particularly adapted for assembly with the coil of goods to be wound upon it with a minimum of labor and without soiling or injuring the goods in the assembly.

Accordingly, the invention proceeds upon the principle of constructing the reel with a core or foundation having a non-round opening which adapts it for non-rotatable 30 mounting upon a stationary shaft, two disk-like flange members applied axially to the core, and a sleeve surrounding the core between the flange members with freedom of rotation relatively to the core and flange members, and having the goods coiled thereon; at least one of the flange members being united with the core member through 35 means which overlie the flange members and interengage with the bore of the core, so that the reels may be supplied with one of the flange members assembled and the other flange member disassembled therefrom, and the sleeve, after having its tape coiled thereon, in a separate winding machine, can 40 be slipped in place over the unobstructed end of the core and permanently secured by means, preferably a flanged thimble, embracing the flange member and interengaging with the core-member.

50 In the accompanying drawing—

Figure 1 is a perspective view of the segregated parts of a reel embodying the invention.

Figure 2 is a side elevation of a suggested form of device for winding the tape or 55 other goods upon the sleeve.

Figure 3 is a face view of the reel shown in Figure 1, with one of its confining flanges omitted, and having in place thereon the coil of goods prepared by the device of Figure 2.

Figure 4 is an axial section of a reel, its coil of goods, and a suggested means for 60 assembling the separately formed flange member.

1 represents the confining flanges of a reel and 2 the foundation core thereof upon which the flanges are secured, and which has a non-round opening 3 which adapts it for non-rotatable mounting upon a shaft, 70 and 4 represents a sleeve or collar which surrounds the core 2.

As shown in Figures 3 and 4, the sleeve 75 has wound upon it a coil 5 of tape, and it fits the core 2 with sufficient looseness to permit the coil of tape to revolve in unwinding and paying out portions of the tape as the same may be required. The reel is furnished with at least one of its flanges 80 disassembled therefrom, and in order that it may be readily assembled therewith, a thimble 6 is provided which fits the opening 7 in the disk 1 and enters the axial recess or bore 3 of the core member 2. Thimble 6 is provided with embracing lips 8 which adapt 85 it to confine the flange 1 to the core 2 and its axially extending portion as well as the opening 7 in the disk, and the recess 3 in the core member is made of conforming non-round section so that the thimble 90 assembles the disk in definite and fixed relation to the core member. To secure the thimble in the core member, it is simply necessary to indent or develop radial spurs or projections 9 (Figure 3) on the portion 95 thereof that is within the core member, as for instance, by forcing a mandril 10 into displacing relation with one or more punches 11, as suggested in Figure 4. It will be seen that the thimble 6 serves as an 100 assembling member for the core and flange, it being simply necessary to place the assembled thimble 6, flange 1, and core member 2 with its originally attached flange member and separately formed coil of goods 105 5, over the upstanding neck 12 of the as-

sembly.

sembling table 13, and then subject the appropriate thimble to the punching operation to interlock it with the surrounding wall of the core member 2.

- 5 When assembled upon its reel as herein described, the coil 5 of goods will be free to rotate while the reel is held stationary, and pay out the goods as required without interference between a plurality of reels that 10 may be mounted upon a single shaft or without tendency of one reel to induce rotation in the others. To separately prepare the coil 5 with the goods, the sleeve 4 may be mounted upon any suitable winding machine, such, for instance, as the revolving head 14 carrying pins 15 upon which the sleeve is adapted to fit.

I claim:

1. A reel for tape and other like goods, 20 comprising an externally cylindrical and internally non-cylindrical core member adapted to receive a coil of goods and having an axial recess, flange members for confining the goods upon the core member, a least one 25 of which flange members is separately formed, and a thimble passing axially through the separately formed flange member and entering the recess of and engaging with the core member; said thimble 30 forming to the interior of the core and being provided on its outer end with radially extending lips that overlie the outer face of the separately formed flange member.

2. A reel for tape and other like goods, 35 comprising an externally cylindrical and in-

ternally non-cylindrical core member, a sleeve member revolvably mounted on said core member adapted to receive a coil of goods and having an axial recess, flange members for confining the goods upon the core member, at least one of which flange members is separately formed, and a thimble passing axially through the separately formed flange member and entering the recess of and engaging with the core member; the 40 portion of the thimble that enters the core member being radially displaced to interlock it with the wall of said recess.

3. A reel for tape and other like goods, comprising an externally cylindrical core 50 member adapted to receive a coil of goods and having an axial recess, flange members for confining the goods upon the core member, at least one of which flange members is separately formed, and lies against the 55 end of the core member, a sleeve rotatably mounted on said core member and axially confined by the flanges and a thimble passing axially through the separately formed flange member and entering the recess of 60 and engaging with the core member; the recess of the core member, the thimble, and the portion of the flange member surrounding the thimble being of non-round section and conforming one to another, and thereby 65 retaining non-rotatable assembly of said parts.

Signed at Chicago, Illinois, this 2nd day of January, 1923.

JOHN W. THOMPSON.
